[57] CLAIM

The ornamental design for a weapon case, as shown and described.

DESCRIPTION

FIG. 1 is a front elevational view of a first embodiment of a weapon case showing my new design;

FIG. 2 is a rear elevational view thereof;

FIG. 3 is a bottom plan view thereof;

FIG. 4 is a right end elevational view thereof;

FIG. 5 is a left end elevational view thereof;

FIG. 6 is a top plan view thereof; and,

FIG. 7 is an isometric view thereof opened with the removable foam in the upper part being partially removed for clarity of illustration.

The weapon case includes a D-ring seal on one portion and a flat seal on the other portion.
